REFRIGERATING SYSTEM

Application filed November 20, 1930. Serial No. 496,845.

This invention relates to a refrigerating system, and has to do particularly with a novel method and apparatus for utilizing dry ice or solidified CO_2 as a refrigerating medium and source of power.

The low temperatures resulting from the physical phenomena in the changing of the solidified CO_2 back to the gaseous state are universally made use of in many ways. The present invention not only makes use of such low temperatures in the evaporation of dry ice but also makes direct use of the gases produced by the direct change from a solid to a gas, in materially assisting in the transfer of heat to suitable remotely positioned cooling units or devices.

More specifically, the present invention resides in the provision of a complete automatic refrigerating unit wherein a cake of solidified CO_2 serves as the sole refrigerating medium. The circulating brine is brought to very low temperatures by contact with the solid CO_2 and then conducted to the cooling unit much the same as in a standard mechanically operated refrigerating system. This circulation of the brine is accelerated and made absolutely positive by utilizing the gases evolved in the evaporation of the solid CO_2 .

Other features reside in the manner of introducing the CO_2 gas into the brine to cause positive circulation thereof, together with details of the system and structure as will be more clearly brought out in the specification and claims.

In the drawings:

Fig. 1 is a vertical sectional view of one form of structure embodying the present invention, a portion thereof being somewhat diagrammatic.

Fig. 2 is an enlarged fragmentary view of a portion of the air pump or what might be termed an aspirating device.

While the present invention should have an almost universal use, it is particularly adapted at the present time for use in places where mechanical refrigeration cannot be depended upon, such as, for instance, in railway dining cars and the like. It is also invaluable for

use in retailing and storing quickly frozen foods.

Any suitable container and cooling unit may be utilized in carrying out the invention, and in the embodiment illustrated I have shown a suitable container 1 for receiving the cake 2 of solidified CO_2 . This container may be made of aluminum or other material of good conductivity. Suitable brine conducting coils 3 may be arranged within or in heat conducting relation to the container 1 but I preferably desire to position these coils 3 in direct contact with the cake of solid CO_2 2; that is, the CO_2 ice may be directly supported by the coils and/or positioned inside of the coils.

An annular receiver 4 preferably surrounds the container 1 and this receiver is adapted to contain a definite supply of brine 5. This brine may consist of calcium chloride or other substance having a relatively low freezing point. The coils 3 are directly connected to the supply of brine 5 and in turn conduct the brine to a suitable cooling unit which may be generally designated 6. It will be understood that this cooling unit may be positioned at any point adjacent to or remote from the main container 1, the point being that the refrigerated brine is conducted to a suitably designed and positioned cooling unit to accomplish the desired refrigerating effect much the same as in any standard refrigerating system. In the particular embodiment shown, the cooling unit consists of what might be termed an ice maker or storage and dispensing cabinet for quickly frozen foods, in that a series of sharp freezing storage compartments 7 are surrounded by the cooling coils 8. If desired, the compartment 7 may be formed directly in artificial stone as shown in Fig. 1. This artificial stone may be plastically applied around the forms for the compartments, the coils, and the receiver 4 so that a massive hold-over is formed for the entire unit.

To obtain positive continuous circulation of the brine through the coils 3 and 8 I preferably conduct the brine through an enlarged cylinder 9 and from there to a point 10 within the brine receiver 4. A relatively small

conduit 12 is positioned within the main container 1 and is adapted to conduct the evaporated CO₂ under a slight pressure to a conduit 13 extending within the cylinder 9. To 5 control the pressure and flow through this conduit 12 I preferably provide a suitable valve 14 and a pressure relief valve 15. I have found from experiment that approximately ten pounds pressure gives the best results for a unit similar to the one shown in the drawings, with the result that all surplus pressure developed in the container 1 will be released by the valve 15.

The conduit 13 within the cylinder 9 is 15 preferably provided with a series of laterally extending apertures 16, as best shown in Fig. 2. I have found that in a device of the type illustrated that a quarter-inch pipe 13 with the apertures 16 spaced approximately 20 six inches apart gives the best results. By using the laterally arranged apertures 16, the CO₂ gas under slight pressure will be discharged laterally to form gas pistons, such gas pistons rising because of the relative 25 specific gravity with the result that cylindrical slugs of brine are raised upwardly and intermittently discharged from the top of the brine conduit at the point 10. The discharged CO₂ gases will pass upwardly through the 30 top of the annular receiver 4 and may be conducted to the atmosphere in any suitable manner, as by means of a suitable port or ports 17.

By using a glass cylinder 9 I have found 35 that by increasing the pressure within the cylinder 1, and hence in the conduit 12, the CO₂ gas will be discharged upwardly in small streams through the brine instead of raising the brine itself; in other words, instead of forming complete gas pistons, the 40 gases under the higher pressures merely cut their way through the brine and are discharged through the top of the conduit simply as gas.

In operation, the system having been filled 45 with brine, the charge or cake of solidified CO₂, may be positioned within the container 1, the top 18 closed down and the insulated cover 19 positioned in place. As the brine 50 will be initially at a relatively high temperature it will be obvious that the solid CO₂ will start to evaporate with great rapidity, cooling the brine within the coils 3 to a very low temperature. Of course, this cooled brine 55 tends to flow towards the lower ends of the coils 8 but circulation is greatly accelerated by the pump action within the cylinder 9. As the CO₂ evaporates a predetermined pressure will be maintained within the container 60 1 and this CO₂ under the predetermined pressure is conducted through the coil 12 and into the apertured conduit 13. This CO₂, under slight pressure will be discharged laterally from the apertures 16 to form gas pistons, as 65 best shown in Fig. 2. Due to the difference

in specific gravity, these gas pistons will raise the separated slugs of brine upwardly and discharge the same out the top of the conduit at the point 10 much the same as if a reciprocating pump were being used.

With this positive circulation the entire refrigerating system, or in other words, the entire supply of brine will be gradually lowered to a temperature substantially the same as that originally created in the chamber 1 due to the evaporation of the solid CO₂. The constantly maintained supply of brine 5 around the outside of the container 1 will materially reduce any heat transfer from the container 1 with the result that once the system is lowered to the desired low temperature, the evaporation of the CO₂ ice will be materially reduced.

It will thus be seen that I have provided a positive refrigerant circulating system having no moving mechanical parts of any kind. A supply of CO₂ ice sufficient to last some twenty-four to forty-eight hours may be initially placed within the unit with the result that low temperature refrigeration is positively obtained and maintained for a predetermined period. It will be understood that the various details of construction may vary considerably and still come within the bounds of the present invention; the size and position of the conduit 12 may be varied and it may be found that the pump action within the cylinder 9 may be obtained in different ways than that disclosed. The essence of this part of the invention is the fact that evaporated CO₂ is utilized to promote positive circulation of the brine.

It will further be understood that any convenient form of cooling unit may be used as the circulation of the brine permits the system to be adapted to any desired design of cooling unit or storage space. As the available commercial supply of solid CO₂ is rapidly increasing and the cost of the same is just as rapidly decreasing, it will be obvious that quick freezing temperatures or at least temperatures sufficient to maintain quickly frozen foods in the proper state of preservation may be readily and easily obtained and at relatively small expense; especially as compared with the expensive refrigerating apparatus necessary to maintain relatively low temperatures.

It will be obvious that I am in no way limited to any particular form of coils for circulating brine and that the coils 3 may be readily dispensed with, the charge of dry ice placed directly in the container 1, and the coils 8 connected directly to the brine reservoir. The positive circulation in combination with a remote controlling unit are the essential features and I have found that if the CO₂ take-off is closed for just a few minutes that a calcium chloride brine will freeze and clog up the system. However, as long as positive

circulation continues the brine is prevented from freezing. In a unit of the type illustrated using a very small amount of brine and with an ice maker cooling unit having a capacity of one thousand and eight ice cubes, I have been able to maintain a temperature of between 30° and 40° F. below zero for a period of approximately eight hours with thirty pounds of solid CO₂.

10 What I claim is:

1. A refrigerating system, comprising a container for receiving a charge of solid CO₂, refrigerant circulating means positioned in direct heat conducting relation with said solid CO₂, said means extending to and forming a part of a cooling unit, means for controlling the escape of CO₂ gas from said container, and means for positively circulating the refrigerating medium in said circulating means.

20 2. A refrigerating system, comprising a container for receiving a charge of solid CO₂, refrigerant containing and circulating means positioned in heat conducting relation with said container, said means extending to and forming a part of a cooling unit, means for controlling the escape of CO₂ gas from said container to permit evaporation of said CO₂ directly from a solid to a gas, and means for positively and continuously circulating the refrigerating medium through said first named means.

30 3. A refrigerating system, comprising a container for receiving a charge of solid CO₂, refrigerant circulating means positioned in direct heat conducting relation with said CO₂ container, said means extending to and forming a part of a cooling unit, said container being constructed to permit change of said solid CO₂ to a gas, and means for conducting such evaporated CO₂ gases into the refrigerant stream to accelerate circulation thereof.

40 4. A refrigerant system, comprising a container for receiving a charge of solid CO₂, refrigerant circulating means for positioning the refrigerant in direct heat conducting relation with said solid CO₂, said means extending to and forming a part of a cooling unit, and means actuated solely by the pressure developed by the changing of the solid CO₂ to a gas for positively circulating refrigerant through the circulating means.

50 5. A refrigerating system, comprising a cooling unit, means for conducting refrigerant to and from said cooling unit, means of the type adapted to change directly from a solid state to a gaseous state to produce a refrigerating effect positioned in constant and direct heat conducting relation with a portion of the supply of refrigerant, and means actuated by the gas produced by said charge for causing positive circulation of the refrigerant through the cooling unit.

60 6. Refrigerating apparatus comprising a refrigerant circulating system, a solid CO₂ chamber, a conduit connected into the said

chamber for conducting the evaporated CO₂ into the refrigerant system, said conduit having one or more apertures for discharging the CO₂ gases into the refrigerant stream to effect positive circulation thereof.

70

7. Refrigerating apparatus of the type described, comprising a refrigerant circulating system, a solid CO₂ chamber, a conduit connected into the said chamber for conducting the evaporated CO₂ into a conduit forming part of the refrigerant system, said CO₂ and refrigerant conduits being positioned substantially vertically, and one or more apertures extending laterally from said CO₂ conduit for projecting a charge of gas into the refrigerant stream to cause positive circulation thereof.

75

8. A refrigerating system comprising a solid CO₂ container, brine coils passing in heat conducting relation to said container and extending into and forming a part of a cooling unit, means for maintaining a predetermined pressure within the container and means for conducting the CO₂ gases under said predetermined pressure into the brine in the form of gas pistons, said gas pistons rising and carrying along slugs of brine whereby to cause positive and continuous circulation of the brine during evaporation of the solid CO₂.

85

9. A refrigerating system comprising a cooling unit, a solid CO₂ container, a brine receiver adjacent the container, brine coils passing in heat conducting relation to said container and extending into and forming a part of the cooling unit, means for maintaining a predetermined pressure within the container and means for conducting the CO₂ gases under said predetermined pressure into the brine in the form of gas pistons, said pistons rising and carrying along slugs of brine whereby to cause positive and continuous circulation of the brine during evaporation of the solid CO₂.

95

10. A method of refrigeration which consists in chilling a brine by bringing it into heat exchange with a body of solid carbon-dioxide, circulating the brine thus chilled in heat exchange relation to the substance to be refrigerated, bringing the brine thus warmed into heat exchange relation with the solid carbon-dioxide and causing the brine to thus circulate by injecting into said brine some carbon-dioxide gas evaporated from said body of solid carbon dioxide.

110

11. A refrigerating system comprising a solid CO₂ container, a brine receiver surrounding said container, brine circulating means passing in heat conducting relation to said container and extending into and forming a part of a cooling unit, means for maintaining a predetermined pressure within the CO₂ container and means for conducting the CO₂ gases under said predetermined pressure into the brine in the form of gas pistons, said gas pistons rising and carrying along

115

120

125

130

slugs of brine into the brine receiver whereby to cause positive and continuous circulation of the brine during evaporation of the solid CO₂.

5 12. A method of refrigerating with solid CO₂ as the cold producing medium which comprises providing a cyclic path for brine, cooling the brine by evaporation of the solid CO₂, and circulating the brine in its cyclic 70 path by the gas power produced by the evaporation of the solid CO₂.

13. A refrigerating system, comprising a solid CO₂ container, a brine receiver surrounding said container, brine circulating 15 means positioned in direct heat exchange relation to said container and extending into and forming a part of a cooling unit, means actuated by the gas evaporated from said body of solid CO₂ for positively circulating 20 the brine and causing the brine to pass into direct heat exchange relation with the CO₂ container and then through the cooling unit, and means for controlling the flow of gas evaporated from said body of solid CO₂ to 25 regulate the circulation of refrigerant by said gas.

14. A method of refrigeration which consists in chilling a brine by bringing it into heat exchange relation with a body of solid 30 carbon dioxide, circulating the brine thus chilled in heat exchange relation to the substance to be refrigerated, bringing the brine thus warmed into heat exchange relation with the solid carbon dioxide and utilizing 35 the potential energy of the carbon dioxide gas evaporated from said body of solid carbon dioxide to circulate the brine.

15. A refrigerating system, comprising a container for receiving a charge of solid CO₂, 40 refrigerant circulating means positioned in direct heat conducting relation with said container, said means extending to and forming a part of a cooling unit, means for controlling the pressure within the container so as to 45 maintain the evaporated CO₂ in gaseous form, means for positively circulating the refrigerating medium in said circulating means, and means for controlling the rate of said circulation.

50 16. A refrigerating system, comprising a container for receiving a charge of solid CO₂, refrigerant circulating means positioned in heat conducting relation to said container, said means conducting the cooled refrigerant 55 into heat exchange relation with a cooling unit, said container being constructed to maintain all the evaporated CO₂ in the container as a gas, means for positively circulating the refrigerant medium in said circulating means, and means for controlling the rate of said circulation.

17. A refrigerating system, comprising a cooling unit to maintain a certain predetermined temperature, a container for receiving 65 a charge of solidified CO₂, a supply of

brine, means for conducting the brine into direct heat exchange relation with said charge of CO₂ and into direct heat exchange relation with said cooling unit, said container being constructed to so control the 70 pressure in the container as to maintain the evaporated CO₂ as a gas, and means for producing a positive circulation of brine throughout the system, said means being regulable to control the rate of circulation of 75 said brine.

18. A refrigerating unit comprising a casing, a cooling unit within the casing for receiving a substance to be cooled, a container within the casing for receiving a charge of solid CO₂, a supply of non-volatile liquid, means for conducting the liquid into wiping contact with the walls of said container and into heat exchange relation with the cooling unit, means for positively circulating the 80 liquid in the system, and means for regulating the rate of said circulation to control the degree of said wiping action and the temperature of said cooling unit.

In testimony whereof I affix my signature. 90
